UNITED STATES PATENT OFFICE.

WILLIAM HEISER, OF BUFFALO, NEW YORK.

DESIGN FOR A BOLT-WASHER.

SPECIFICATION forming part of Design No. 26,563, dated January 26, 1897.

Application filed December 4, 1896. Serial No. 614,494. Term of patent 14 years.

To all whom it may concern:

Be it known that I, WILLIAM HEISER, a citizen of the United States, residing at Buffalo, in the county of Erie and State of New York, have invented and produced a certain new and original Design for a Bolt-Washer, which is fully set forth and described in the following specification, reference being had to the accompanying sheet of drawings, forming part thereof, and in which—

Figure 1 is a perspective view of a bolt-washer of my new and original design. Fig. 2 is a transverse sectional elevation in line *x-x* of Fig. 3, Fig. 3 being a plan of said washer.

Like parts are designated by corresponding letters of reference in all the figures.

This design relates to the form of washers for machine-bolts, and especially that class of bolts designated as "carriage-bolts," and is characterized by the curvature of the sides of the body in conjunction with a flat or plane top surface.

Describing the form of my design for a bolt-washer: It consists of a rectangular body portion A, having centrally a rectangular aperture B, the four outer sides of said body portion having outwardly and upwardly curved shape, while the top surface is a plane or flat surface D, as clearly shown in the drawings. This bolt-washer is adapted for use upon that class of bolts usually designated "carriage-bolts."

I claim—

The design for a bolt-washer, herein shown and described.

In testimony that I claim the foregoing as my new and original design I have hereunto set my hand in the presence of two subscribing witnesses.

WM. HEISER.

Attest:

ALBERT G. HEISER,
MICHAEL J. STARK.
